UNITED STATES PATENT OFFICE.

ROBERT SCHOFIELD, OF SOUTH DARTMOUTH, MASSACHUSETTS, ASSIGNOR TO DRAPER CORPORATION, OF HOPEDALE, MASSACHUSETTS, A CORPORATION OF MAINE.

BOBBIN CLEANER.

Application filed January 12, 1925. Serial No. 2,036.

To all whom it may concern:

Be it known that I, ROBERT SCHOFIELD, a citizen of the United States, and a resident of South Dartmouth, in the county of Bristol and State of Massachusetts, have invented an Improvement in Bobbin Cleaners, of which the following description, in connection with the accompanying drawings, is a specification, like characters on the drawings representing like parts.

This invention relates to bobbin cleaners or machines for removing waste yarn from bobbins. In filling replenishing looms it is now the common practice to replenish filling prior to its complete exhaustion and the ejected or discarded filling carrier or bobbin usually contains a small amount of yarn which must be stripped or cleaned from the bobbin prior to again placing upon the bobbin its fresh load of yarn. Where the yarn is stripped or cleaned from the bobbin by mechanical means, as has been heretofore practiced, there is danger of injuring the bobbin itself during the stripping or cleaning operation, and in order to overcome this objectionable action of the bobbin cleaners or strippers it has heretofore been proposed also to remove the waste yarn from the bobbins or yarn carriers by air currents which act upon the yarn on the bobbins or carriers and withdraw it therefrom.

The present invention relates to the last mentioned type of bobbin cleaners or strippers, and has for its object to provide a machine acting on the air cleaning principle which will more effectually remove the waste yarn from bobbins.

In accordance with the present invention, the bobbins containing waste yarn are placed upon a holder and the yarn ends are presented to the inlet opening of an air conduit through which air currents may be induced by current inducing means. Between the air inducing means and conduit, the present invention provides means for separating the waste yarn from the air currents and gathering them into a receptacle from which they may be removed from time to time, while the air currents themselves may pass unimpeded under the impulse of the current inducing means.

The invention and new combination of parts will best be made clear from the following description and the accompanying

drawings of one good form of a machine embodying the invention.

In the drawings:

Fig. 1 is a perspective view of a machine for cleaning waste yarn from bobbins embodying the present invention; and

Fig. 2 is an enlarged cross-sectional view of the yarn collecting tank and baffle.

In accordance with the present invention, as shown, the air currents are induced by a suitable fan or air current inducing means, operated in the present instance by suction, and the ends of the yarn from the bobbins to be cleaned are presented to the inlet opening of an air conduit connected with the current inducing means, while between the air inducing means and conduit is interposed a yarn collecting and baffle tank.

In the drawings, Fig. 1, the air inducing means is shown as a pump or air suction means, indicated at 1, which may be actuated from any suitable source of power, and as the details of such mechanism constitute no essential part of the present invention they are not herein shown and described except as to the relative position of such means and the other portions of the machine.

Mounted upon a suitable support or stand 2 is a projection or upright 3 on which is pivotally mounted at 4 a bobbin support carrying arm 5 capable of swinging movement about its pivotal mounting 4. Each of the arms, one at each side of the pivotal support 4, has mounted thereon a bobbin holder which as shown comprises a disk 6 having a series of pins extending upwardly therefrom. Above the pins 7, which are utilized for holding individual bobbins, is another disk 8 provided with a series of yarn guides 9, and the two disks 6 and 8 are connected by a barrel 10 which may be appropriately supported for rotary movement upon its supporting arm 5, as indicated by dotted lines 11, Fig. 1. The guides 9 may be variously contrived and are herein shown as of the pig-tail type, one of said pig-tail guides being carried by the disk 8 above each of the pins 7 and preferably, though not necessarily, attached to the peripheral portion of the disk 8.

The bobbins having the waste yarn thereon may be supplied to the machine from a stand 12 which is herein shown as divided into two portions by the projection 13, one

for the bobbins 14 having the waste yarn thereon, and the other for the bobbins when the waste yarn has been removed therefrom.

Between the air current inducing means 5 and the bobbin support or holder is a waste yarn collecting tank 15 having a door 16 at its lower portion from which the waste yarn may be removed from time to time.

The yarn collecting tank 15 is preferably formed cylindrical and has its top wall 17 formed with an opening 18 for the reception of the baffle 19. The baffle 19 comprises a substantially cylindrical member having the top plate 20, the edges of which at 21 rest upon the top wall 17, while the cylindrical portion of the baffle extends through the opening 18 from which it may be removed from time to time when desired.

Between the baffle 19 and the air inducing means 1 is the suction pipe 22, the end of said pipe extending through an opening 23 in the top wall 20 of the baffle and forming therewith a substantially air-tight joint.

The baffle 19 has an open lower portion 24 which is covered by a screen 25 which may be secured about the edges of the opening 24 at 26, as shown, the construction being such that upon operation of the air inducing means 1, air currents will be created through the baffle 19 and passed, as indicated by the arrows in Fig. 2, into the pipe 22 connected with the current creating means.

Connected with the yarn collecting tank 15 is the air conduit 27 which communicates with the tank 15 at a point opposite the solid walls of the baffle which extend downwardly into the yarn collecting tank, as indicated in Fig. 2, the result being that as the air currents are induced through the conduit 27, in the direction indicated by the arrows, Fig. 2, and carry with them the waste yarn ends *a*, such induced currents will strike the solid wall of the baffle presented to the opening 28 of the conduit 27 and will take a downward direction, as indicated by the arrows, thereby permitting the waste ends *a* to travel downwardly into the yarn collecting tank 15, while the air currents themselves will pass about the bottom of the baffle 19 through the screen 25 to the air inducing means. This method of separating the waste yarn ends from the air currents is found to be efficient and practical, in that the travelling yarn ends *a* as they enter the yarn collecting tank will by their momentum pass downwardly in the tank, as indicated in Fig. 2, while the air currents themselves will pass about the solid portion of the baffle and enter through the screen 25 freed from waste yarn. This characteristic operation of the machine is also emphasized from the fact that during the cleaning of a series of bobbins, a plurality of the yarn ends are collected together and withdrawn from the bobbins as the ends are carried by the in-

duced air currents through the conduit 27, such mass of yarn having sufficient momentum to carry them as hereinbefore described, downwardly in the yarn collecting tank, thus freeing them from the air currents which pass through the bottom of the baffle.

The inlet opening 29 of the air conduit is preferably formed flaring or trumpet-like, as indicated in Fig. 1, and is arranged adjacent to or above the bobbin holder. Between the inlet opening 29 of the air conduit and the bobbin holder is a yarn end gathering guide for gathering the ends of the yarn leading from the bobbins and presenting them in bunched relation at the entrance of the air conduit. As shown, the yarn gathering guide 30 has a gathering portion 31 disposed opposite the flaring opening 29 of the air conduit, and may be conveniently supported, as shown, by the collar 32 which may be clamped about the conduit 27 at the base of the flaring end portion 29 thereof.

When a series of bobbins containing waste yarn are to be cleaned or stripped of the yarn thereon, they are placed upon the supporting pins 7 when the bobbin holder itself is in its idle or non-stripping position, as indicated at the right of Fig. 1. The bobbin holder supporting arm 5 is then swung around its pivotal support 4 to place the bobbin holder adjacent the inlet opening of the conduit, as indicated at the left, Fig. 1, and thereupon the attendant pulls a small length of yarn from each bobbin, passes it through its appropriate guide above each bobbin, gathers the several ends of the yarn together and places them over the yarn gatherer at the mouth of the conduit, as indicated in Fig. 1, whereupon the induced air currents passing into the conduit 27 withdraw the yarn end-wise from the bobbins in gathered relation and carry them along with the induced air currents into the yarn gathering tank 15, and since the air conduit 27 has its delivery opening 28 opposite the solid walls of the baffle, the gathered ends of the yarn take a downward course in the yarn collecting tank, while the induced air currents freed of their yarn load, pass about the baffle and upwardly through the screened lower end thereof.

Should it be desirable at any time to clean the baffle it is only necessary to lift the baffle bodily from the yarn collecting tank, remove the accumulation of lint, if there be any, and return the parts into their working relation, as indicated in Fig. 2.

From the construction described it will be apparent that during the stripping or cleaning of a series of bobbins from the bobbin holder opposite or adjacent the inlet of the conduit, the attendant may be placing another series of bobbins on the companion

bobbin holder, and when one series of bobbins has been cleaned the attendant may then turn the supporting arm 5 to carry the cleaned bobbins into their removing position and the bobbins having waste yarn into their position for being cleaned.

What is claimed is:

1. In a machine for removing waste yarn from bobbins, the combination of a holder for supporting a series of bobbins, an air conduit having an inlet opening adjacent said holder, and a series of guides for directing the yarn from said series of bobbins into the path of air currents entering 15 the inlet of the air conduit.

2. In a machine for removing waste yarn from bobbins, the combination of a holder, for supporting a series of bobbins, an air conduit having an inlet opening adjacent 20 the bobbin holder, a series of guides for directing the yarn from said bobbins towards the inlet opening of the air conduit and a gathering guide for gathering the series of yarns opposite the entrance to the 25 air conduit.

3. In a machine for removing waste yarn from bobbins, the combination of a holder for supporting a series of bobbins with waste yarn thereon, an air conduit having 30 an inlet adjacent said holder, and a yarn gathering guide for gathering the yarn ends from the series of bobbins and presenting the gathered yarn ends to the inlet of the air conduit.

35 4. In a machine for removing waste yarn from bobbins, the combination of a holder for supporting a series of bobbins with waste yarn thereon, an air conduit having a flaring inlet adjacent said holder, and a 40 yarn gathering guide for gathering the yarn ends from the series of bobbins and presenting the gathered yarn ends to the inlet of the air conduit.

45 5. In a machine for removing waste yarn from bobbins, the combination of a bobbin holder comprising a support having a series of bobbin holding pins, a guide for directing the yarn ends from each bobbin, a yarn gathering guide for gathering the yarn, an 50 air conduit having an inlet opposite the yarn gathering guide, and means for inducing air currents into said inlet.

55 6. In a machine for removing waste yarn from bobbins, the combination of a yarn gathering tank, an air conduit communicating with said tank, a baffle extending into said tank and having imperforate side walls opposite the air conduit and a bottom screen wall, and means for inducing air currents 60 through said conduit to cause the waste yarn and air currents to strike against the exterior of the imperforate side walls of the baffle and be deflected downwardly and the air currents to pass about the lower edges

of the side walls upwardly through the bottom screen wall of the baffle freed from all the waste yarn.

7. In a machine for removing waste yarn from bobbins, the combination of a yarn gathering tank, a baffle extending into said tank and provided with a reticulated bottom wall and imperforate side walls, an air conduit communicating with the tank opposite an imperforate side wall of the baffle to deflect yarn and air currents entering the 75 tank through the conduit, and means for inducing air currents through the conduit, tank, and baffle.

8. In a machine for removing waste yarn from bobbins, the combination of a yarn gathering tank, a baffle extending into said tank and provided with a reticulated bottom wall and imperforate side walls, an air conduit communicating with the tank opposite an imperforate wall of the baffle to 80 deflect both the yarn and air currents entering the tank through the conduit, means for presenting yarn from bobbins to the air conduit, and means for inducing air currents through the conduit, tank, and baffle. 85

9. In a machine for removing waste yarn from bobbins, an air conduit having an inlet opening, a guide for presenting yarn ends from a series of bobbins to the inlet opening to be removed from the bobbins in a direction from the ends thereof, a yarn gathering tank, a baffle in said tank having an imperforate wall opposite the delivery end of the conduit, and means for inducing air currents through the conduit, tank, and baffle. 95

10. In a machine for removing waste yarn from bobbins, an air conduit having an inlet opening, a yarn gathering guide opposite the inlet opening for presenting a plurality 105 of yarn ends to the inlet opening to be removed from the bobbins, a yarn gathering tank, a baffle in said tank having imperforate side walls and a screen bottom wall, and means for inducing air currents through the conduit, tank, and baffle. 110

11. In a machine for removing waste yarn from bobbins, the combination of a yarn gathering tank having an opening, a removable baffle extending through said opening 115 and having imperforate side walls and a perforated bottom wall, an air conduit communicating with the tank opposite an imperforate side wall of the baffle for delivery of air currents and yarn ends against said wall outside the baffle, means for inducing air currents through the conduit, tank and the perforated bottom wall of the baffle, and means for presenting yarn ends to the inlet of the air conduit. 120

In testimony whereof, I have signed my name to this specification.

ROBERT SCHOFIELD.
